UNITED STATES PATENT OFFICE

NORRIS F. MCNAUGHT AND EDWARD H. PETERSON, OF CHICAGO, ILLINOIS, ASSIGNORS
TO DURO METAL PRODUCTS COMPANY, OF CHICAGO, ILLINOIS, A CORPORATION OF
ILLINOIS

VALVE SPRING COMPRESSOR

Application filed November 9, 1931. Serial No. 573,818.

Our invention relates to a valve spring compressor and is particularly concerned with the provision of an improved device which will compress a valve spring and hold it under compression during the application and/or removal of the pin or key which normally holds the movable abutment of the spring in position.

The present invention provides a device of 10 the class mentioned which, although sturdily constructed, is light and compact, which comprises a minimum of parts, and which for its operation requires but very little effort on the part of the operator.

15 In the accompanying drawings illustrating a preferred embodiment of our invention,

Fig. 1 is an elevational view of the device as it appears when holding a valve spring under compression;

20 Fig. 2 is an elevational view of the device with its jaws in the open position;

Fig. 3 is an elevational edge view of the device with the operating lever and jaws in the positions of Fig. 2; and

25 Fig. 4 is a top plan view of the device.

Similar characters of reference refer to similar parts throughout the several views.

In Fig. 1 of the drawings reference numeral 6 indicates a portion of a removable engine head provided with a valve seat 7, poppet valve 8, valve stem guide 9, valve spring 10, valve spring abutment washer 11 and a washer retaining pin 12, pin 12 extending through a transverse opening in the lower

30 end (in the view shown upper end) of the valve stem. The device of the present invention facilitates the ready removal and insertion of the pin 12 and enables the spring 10 to be relieved from compression, and the pin 35 12 removed, without permitting any possibility for the spring 10 or its abutment washer 11 being thrown away from the engine block, as frequently occurs when valve springs are unrestrained when relieved of compression.

40 45 The device of our invention comprises an L shaped bar, preferably of round stock, comprising arms 14 and 15, the arm 15 having an end 16 offset in a line parallel with arm 14.

50 Mounted on the arm 14 is a movable jaw member in the form of a casting 17 provided

at one end with spaced arms 18, 18 having circular openings adapted freely to receive the arm 14 of the L shaped bar. The other end of the casting 17 is bifurcated as indicated at 19, the underside of the bifurcation 19 being 55 rabbeted at 20 for the reception of the valve spring abutment washer 11 to which we previously have alluded.

At 21 we have shown the power arm of an operating lever which is bifurcated to provide work arms 22, 22, the arms 22, 22 embracing the portion 14 of the L shaped bar and being pivoted thereto by pin 23. The arms 22, 22 of the operating lever are pivotally connected to the adjacent ends of parallel links 24, 24 by rivets 25, 25, the other ends of such links being pivoted to the casting 17 by a pivot pin 26. The arrangement is such that when the operating lever is in the position shown in Fig. 1, the axis represented by the pivot rivets 25, 25 lies to the left of a straight line drawn between the axes of the pivot pins 23 and 26. Therefore, the arms 22, 22, links 24, 24 and their several pivots, constitute a locking toggle which tends to hold all of the parts, in the positions shown in Fig. 1, against pressure of a valve spring tending to move apart the jaws of the device, i. e. the casting bifurcation 19 and the portion 16 of the L shaped bar. The arms 22, 22, links 24, 24, and their several pivots, also prevent the bifurcated portion 19 of the casting 17 from being rotated out of alignment with the portion 16 of the L shaped bar.

In employing a device of our invention to remove the valve shown in Fig. 1, the operating lever is moved to the position of Figs. 2 and 3, the bifurcated portion 19 of the casting 17 being applied to the valve spring washer 11 with the latter received in the rabbet 20 of the bifurcated portion. At the same time, the jaw portion 16 of the L shaped bar is applied to the exposed portion of the valve head.

The operating lever now is swung away from the L shaped bar, causing the several parts to be moved to and locked in the position shown in Fig. 1. In this last mentioned situation, the valve spring is held under greater than normal compression, with the 100

result that the pin 12 readily may be removed. The valve spring thereupon gradually may be relieved from compression by moving the operating lever from the position of Fig. 1 to the position of Figs. 2 and 3. When this has occurred the valve, its spring, and the abutment washer of the latter may be removed for extension, replacement and repair.

- 10 In view of the foregoing description, it will be obvious to those skilled in the art how the device of our invention may be utilized when replacing the valve, its spring, spring abutment washer and retaining pin in operative relation upon the engine.
- 15

Having thus illustrated and described our invention, what we claim is new and desire to secure by Letters Patent of the United States, is:

- 20 1. A device of the class described comprising a substantially L shaped member having its base arm offset in a line parallel to its other arm, a movable jaw member provided at one end with spaced arms receiving and adapted to reciprocate upon the last mentioned arm of the L shaped member, said movable jaw member having a bifurcated end disposed in alignment with the aforesaid offset portion of the L shaped bar, said bifurcated end being rabbeted on the surface thereof opposed to the said offset portion, a lever pivoted to the L shaped member between the aforesaid spaced arms of the movable jaw member, and a link pivotally connecting said lever with the movable jaw member, said lever and link and their several pivots constituting a locking toggle, substantially as and for the purpose set forth.

- 60
- 65
2. A device of the class described comprising a frame bar provided at one end with means for engaging a valve head, a jaw member having a bifurcated end in alignment with and movable toward and away from the valve engaging means of the frame bar, said jaw member having a pair of spaced arms slidably mounted on the frame bar a lever pivoted to the frame bar between the aforesaid spaced arms of the jaw member, and a link pivotally connecting said lever and said jaw member, said lever and link and their several pivots constituting a locking toggle, substantially as and for the purpose set forth.

In witness whereof, we hereunto subscribe our names this 5th day of November, 1931.

NORRIS F. MCNAUGHT.
EDWARD H. PETERSON.
